UNITED STATES PATENT OFFICE.

HENRY W. A. FUHRMANN, OF ALHAMBRA, CALIFORNIA.

INTAKE LOCK FOR MOTOR VEHICLES.

Application filed October 6, 1921. Serial No. 505,759.

To all whom it may concern:

Be it known that I, HENRY W. A. FUHRMANN, a citizen of the United States, residing at Alhambra, in the county of Los Angeles and State of California, have invented new and useful Improvements in Intake Locks for Motor Vehicles, of which the following is a specification.

My invention relates to a device particularly intended for preventing the unauthorized use of motor vehicles, said device being in the nature of a lock for controlling the combustible mixture that passes from the carburetor to the intake manifold of an internal combustion engine; the principal objects of my invention being to provide a relatively simple and practical device that is positioned between the carburetor and the intake manifold of the engine, a portion of which device is adapted to be removed so as to admit air into the inlet passageway from the carburetor to the cylinders of the engine, which action destroys the partial vacuum produced in the carburetor, and consequently preventing the engine with which the device is associated from receiving sufficient gaseous fuel to enable it to be operated.

A further object of my invention is to provide a device having means that automatically shifts into position to partially or fully close the inlet passageway for the gaseous fuel when a portion of the locking device is removed to admit air to said inlet passageway and destroy the partial vacuum therein.

Further objects of my invention are to provide a locking device that may be easily and cheaply produced and which will be very effective in performing its intended functions, preventing the unauthorized use of the engine.

With the foregoing and other objects in view, my invention consists in certain novel features of construction and arrangement of parts that will be hereinafter more fully described and claimed and illustrated in the accompanying drawings, in which:

Figure 1 is an elevational view of an internal combustion engine and showing the locking device contemplated by my invention in position between the carburetor and the intake manifold of the engine.

Fig. 2 is an enlarged horizontal section taken through the center of the locking device and showing the movable plates thereof in position to partially close the inlet

passageway from the carburetor to the intake manifold, consequently partially cutting off the flow of gaseous fuel through said passageway.

Fig. 3 is a horizontal section similar to Fig. 2 and showing the key member inserted in the device and the movable plates therein shifted into position to permit the passage of gaseous fuel through the intake passage.

Fig. 4 is an elevational view of the device and showing the means utilized for locking the key plate in its inserted position within said device.

Referring by numerals to the accompanying drawings which illustrate a practical embodiment of my invention, 10 designates an internal combustion engine of the type ordinarily employed in motor vehicles, 11 the carburetor provided with the usual tubular gaseous fuel inlet 12, and 13 the intake manifold having a tubular portion that is directly connected to said tubular member 12.

My improved locking device is positioned between the tubular members 12 and 13 and is secured in position by the usual bolts 14 that pass through flanges that are formed on said members 12 and 13.

The body of the device comprises a pair of plates 15 that are practically the same in size and construction, each of said plates being provided with a centrally arranged opening 16 that coincides with the openings or passageways through tubular members 12 and 13. Formed in the inner faces of the plates 15 and on opposite sides of the openings 16 therein are laterally projecting chambers 17 that provide pockets that are adapted to receive plates 18, and which latter co-operate to form a valve that partially closes the opening 16 through the plates 15.

Plates 18 are provided with lateral extensions 19 that occupy recesses 20 formed at the ends of the recesses 17, and passing through the plates 15 and through the end portions of these extensions 19 are pivot pins 21, looped about these pivot pins 21 are the intermediate portions of springs 22, one arm of each spring being seated in the corresponding plate 18, and the opposite end of said spring bearing against a part of one of the plates 15 adjacent to the pivot pin, and said springs act to normally maintain the plates 18 in position to partially close the opening 16.

Formed in the inner faces of plate 15 and extending from one of the outer edges thereof into the recesses 17 are coinciding recesses 23 through which is arranged to slide a key plate 24, and which latter is adapted to engage the plates 18 and swing the same rearwardly away from opening 16 into the pockets 17. This key plate is provided with a centrally arranged slot 25 that receives a pair of ribs 26 on the plates 15, and formed in the upper and lower faces of the key plate are grooves 27 that are adapted to receive ribs 28 that are formed on plates 15 within the recesses 23.

15 The edges of the plates 15 adjacent to the openings or recesses 23 are indented or provided with notches 23^a to the sides of the ribs 26, and which construction renders it difficult to plug or cover the outer ends of 20 the openings formed by the coinciding openings or recesses 23.

Formed in the outer portion of one edge of key plate 24 is a notch 29 that is adapted to receive a retaining member 30 that is 25 pivoted to one of the plates 15, and which arrangement provides means for locking the key plate in inserted position.

When the key plate is inserted in the opening formed by the recesses 23, the inner end 30 of said plate bears against the arms 19 and swings the pivotally mounted plates 18 away from opening 16 into recesses 17, and with the parts so positioned the fuel opening from the carburetor to the intake manifold is 35 maintained and consequently ample gaseous fuel will pass into the engine so that the same may function in its usual manner.

When the owner of the car to which my improved device is applied desires to prevent 40 the unauthorized use of said car, the key plate 24 is removed thereby permitting the plates 18 into position to partially close the opening 16, and at the same time providing a relatively large opening into the passageway 45 which will admit air into said passageway and consequently destroy the partial vacuum existing therein, and as a result it is impossible for the engine to draw sufficient 50 gaseous fuel into its cylinders to enable it to continue in operation.

Thus it will be seen that I have provided a relatively simple, practical and efficient device that includes a member in the nature 55 of a key plate that is adapted to be removed by the owner of the car for the purpose of forming an opening into the gaseous fuel inlet passageway so that it will be impossible to operate the car through failure of the 60 engine to receive sufficient gaseous fuel, and further said device being provided with means that will automatically shift into position to fully or partially close the inlet passageway when the key plate is removed 65 from the device.

It will be understood that minor changes in size, form and construction of the various parts of my improved locking device may be made and substituted for those herein shown and described without departing from the spirit of my invention, the scope of which is set forth in the appended claims.

I claim as my invention:

1. The combination with the gaseous fuel supply pipe of an internal combustion engine, of a member located in said supply pipe and provided with an air inlet opening, and a member normally closing said air inlet opening, but adapted to be removed at will from the machine to prevent unauthorized use of the engine.

2. The combination with the gaseous fuel supply pipe of an internal combustion engine, of a member located in said pipe and provided with an air inlet opening, a member removably positioned in said air inlet opening, and means within the member provided with the air inlet opening for partially closing the fuel inlet passageway therethrough.

3. The combination with the gaseous fuel supply pipe of an internal combustion engine, of a member located in said pipe and provided with an air inlet opening, a member removably positioned in said air inlet opening, means within the member provided with the air inlet opening for partially closing the fuel inlet passageway therethrough, and which fuel passageway closing means is retained in open position when the removable member is positioned within said member having the fuel inlet passageway.

4. The combination with a gaseous fuel supply pipe of an internal combustion engine, of a member positioned in said fuel supply pipe and provided with an air inlet opening, a key plate adapted to normally close said air inlet opening, and a pair of spring pressed plates pivotally arranged within said member and adapted to partially close the fuel inlet passageway therethrough, and which plates are adapted to be engaged by the key and retained in open position when said key plate is inserted in the first mentioned member.

5. The combination with a gaseous fuel supply pipe of an internal combustion engine, of a member positioned in said fuel supply pipe and provided with an air inlet opening, a key plate adapted to normally close said air inlet opening, a pair of spring pressed plates pivotally arranged within said member and adapted to partially close the fuel inlet passageway therethrough, and which plates are adapted to be engaged by the key and retained in open position when said key plate is inserted in the first mentioned member, and means for locking the key plate in position within said member.

6. In a lock for the gaseous fuel supply

5 pipes of internal combustion engines, a housing having an opening adapted to coincide with the gaseous fuel passageway through the fuel supply pipe, there being an 10 opening formed in said housing and leading from the exterior thereof to the fuel passageway therethrough, and a member removably positioned in said opening, this member being in the form of a plate adapted 15 to be removed from the machine to prevent unauthorized operation of the engine.

7. In a lock for the gaseous fuel supply 15 pipes of internal combustion engines, a housing provided with a fuel passageway that is adapted to coincide with the fuel 20 passageway through the supply pipe, there being an air inlet opening formed in said housing and communicating with the fuel inlet passageway therethrough, a key plate 25 adapted to be inserted in said air inlet opening, and means within the housing for partially closing the fuel opening therethrough, and which means is retained in open position when the key plate is inserted in the air inlet 30 opening in said housing.

8. In a lock for the gaseous fuel supply 35 pipes of internal combustion engines, a housing provided with a fuel passageway that is adapted to coincide with the fuel 40

45 passageway through the supply pipe, there being an air inlet opening formed in said housing and communicating with the fuel inlet passageway therethrough, a key plate 50 adapted to be inserted in said air inlet opening, means within the housing for partially closing the fuel opening therethrough, and which means is retained in open position when the key plate is inserted in the air inlet 55 opening in said housing, and means for locking the key plate in position within said housing.

9. In a lock for the gaseous fuel supply 45 pipes of internal combustion engines, a housing provided with a fuel passageway that is adapted to coincide with the fuel 50 passageway through the supply pipe, there being an air inlet opening formed in said housing and communicating with the fuel inlet passageway therethrough, a key plate 55 adapted to be inserted in said air inlet opening, and means within the housing for partially closing the fuel opening therethrough, and which means is retained in open position when the key plate is inserted in the air inlet 60 opening in said housing.

55 In testimony whereof I have signed my name to this specification.

HENRY W. A. FUHRMANN.
